UNITED STATES PATENT OFFICE

2,433,278

DOOR HANDLE, LATCH, AND LATCH
OPERATORGerald V. Jakeway, Grand Rapids, Mich., assignor
to Keeler Brass Company, Grand Rapids, Mich.,
a corporation of Michigan

Application December 8, 1945, Serial No. 633,646

8 Claims. (Cl. 292—66)

1

This invention relates to improvements in door handle, latch and latch operator.

This invention is an adaptation and in some respects an improvement upon the door handle of my copending application, Serial No. 631,616, filed November 29, 1945.

The main objects of this invention are:

First, to provide an improved door handle of the pull trigger type which may be locked to prevent actuation thereof.

Second, to provide an improved door handle of the trigger type which is readily mounted as a unit on an automobile door, refrigerator door, or the like, the movable parts being effectively housed.

Third, to provide a door handle in which the bolt is released and the door opened by an outward pull on the handle.

Fourth, to provide a structure having these advantages which is attractive in appearance.

Objects relating to details and economies of the invention will appear from the description to follow. The invention is defined and pointed out in the claims.

A preferred embodiment of the invention is illustrated in the accompanying drawing, in which:

Fig. 1 is a fragmentary view partially in longitudinal section of a handle embodying my invention in operative relation to a door, the door and other parts being somewhat enlarged.

Fig. 2 is an enlarged fragmentary view partially in transverse section on the broken line 2—2 of Fig. 1.

Fig. 3 is an enlarged transverse section on line 3—3 of Fig. 1.

Fig. 4 is an enlarged fragmentary view in section on broken line 4—4 of Fig. 1.

Fig. 5 is an enlarged fragmentary view partially in section on a line corresponding to that of Fig. 1 showing further details of the structure.

Fig. 6 is a perspective view of the bolt actuating trigger.

In the embodiment of my invention illustrated, 1 represents a door having a chamber 2 therein and provided with an outer panel 3. 4 represents a part of the door casing or frame.

In the embodiment illustrated, the reinforcing plate 5 is secured on the inner side of the panel 3 to extend across the chamber 2 and is provided

2

with an inturned arm 6 constituting an attaching bracket for the handle as will appear as the description proceeds.

The handle comprises an outwardly bowed hollow grip portion 7 suitably conformed to provide a pull grip. As illustrated, the handle is longitudinally tapered, its inner end being of substantially larger dimension than its outer end.

The handle has plate-like supporting brackets 8 welded to its sides to project through the openings 9 and 10 in the outer panel and the reinforcing plate.

The escutcheon 11 is provided for this opening, the inner end of the handle seating in this escutcheon as shown in Figs. 1 and 2. The handle is clamped upon the escutcheon by the screw 12 which extends through the arm 6 and engages the threaded opening 13 in the cross piece 14 of the bracket members 8. This screw is accessible through an opening 15 in the inner edge of the door, the opening being covered when the door is in closed position, as shown in Fig. 1.

The handle grip has a longitudinal slot 16 in its inner side receiving the latch lever 17; this latch lever is pivoted at 18 to the bracket plates 8 and is urged or biased to its initial position by means of the spring 19 arranged within the handle grip. The inner end of the spring is engaged with the latch lever while its outer end 30 is engaged with the outer wall of the grip.

The latch lever is provided with laterally projecting lugs 20 which engage notches 21 in the rear end of the trigger 22 which is pivoted at 23 on the bracket members 8, the pivot 23 constituting a stop limiting the outward movement of the latch lever and consequently the return position of the trigger.

In the embodiment illustrated, the trigger is of U-shape, embracing the portion of the latch lever carrying the lugs. The trigger is provided with a curved nose portion 24 which engages the bolt lever 25 pivoted at 26 to the brackets 27 carried by the supporting plate. The bolt 28 is slidably supported by the rollers 29 on the brackets 27 and is pivotally connected at 30 to the latch lever. The bolt projects through the hole 31 provided therefor in the end wall of the chamber 2 to engage the keeper 32 in the frame.

To lock the latch lever, I provide a bolt 33 which is rotatably mounted in a support 34 car-

ried by the face or outer side of the handle grip, the bolt 33 having locking projections 35 adapted to be swung into the path of the latch lever, as shown by dotted lines at 135, Fig. 1, thereby preventing the actuation of the latch lever. I have not illustrated the details of the lock but have indicated a tumbler type of lock at 36.

When the lock bolt is adjusted to the position shown by full lines in Fig. 1, the latch lever may be actuated by a pull thereof, the latch lever being grasped with the pull handle or grip. However, when the lock bolt is adjusted to the position indicated by dotted lines in Fig. 1, it constitutes a stop preventing the actuation of the latch lever.

At its outer end, the handle grip is provided with a projecting bolt 37 which projects through the supporting plate to be secured thereto by means of the nut 38.

I have illustrated and described my invention in a commercial embodiment thereof. I have not attempted to illustrate or describe certain modifications or adaptations as it is believed that this disclosure will enable those skilled in the art to embody or adapt my invention as may be desired.

Having thus described my invention, what I claim as new and desire to secure by Letters Patent, is:

1. The combination with a door comprising an outer panel, a reinforcing plate mounted on the inner side of said panel and having a laterally disposed arm at the outer end thereof, an inwardly projecting bracket on said plate, said panel and reinforcing plate having registering openings therein, an escutcheon arranged on the outer side of said panel, an outwardly bowed chambered handle grip having a longitudinal slot in its inner side and having inwardly projecting arms at its inner end projecting through said openings, an attaching screw carried by said arm on said reinforcing plate in securing engagement with the inner end of said handle and clamping the same upon said escutcheon, said grip being provided with attaching means at its outer end engaging said plate, a latch lever pivotally mounted within said grip to be retracted in said slot, a spring arranged within said grip to bias said latch lever to its initial position, a trigger notched at its inner end and pivotally mounted between said arms on said grip, said latch lever being provided with studs engaging said notch of said trigger whereby the trigger is actuated on the retracting of the latch lever, a bolt lever pivotally mounted on said bracket in coacting relation to said trigger, and a bolt slidably supported on said bracket and pivotally connected to said bolt lever.

2. The combination with a door comprising an outer panel, a reinforcing plate mounted on the inner side of said panel, an inwardly projecting bracket on said plate, said panel and reinforcing plate having registering openings therein, an outwardly bowed chambered handle grip having a longitudinal slot in its inner side and having inwardly projecting arms at its inner end projecting through said openings, a latch lever pivotally mounted within said grip to be retracted in said slot, a spring arranged within said grip to bias said latch lever to its initial position, a trigger notched at its inner end and pivotally mounted between said arms on said grip, said latch lever being provided with studs engaging said notch of said trigger whereby the trigger is actuated on the retracting of the latch lever, a bolt lever pivotally mounted on said bracket in coacting

relation to said trigger, and a bolt slidably supported on said bracket and pivotally connected to said bolt lever.

3. The combination with a door comprising an outer panel, a reinforcing plate mounted on the inner side of said panel and having a laterally disposed arm at the outer end thereof, an escutcheon arranged on the outer side of said panel, an outwardly bowed chambered handle grip having a longitudinal slot in its inner side and having inwardly projecting arms at its inner end, an attaching screw carried by said arm on said reinforcing plate in securing engagement with the inner end of said handle and clamping the same upon said escutcheon, said grip being provided with attaching means at its outer end engaging said slot, a latch lever arranged within said grip to be retracted in said slot, a spring arranged within said grip to yieldingly urge said latch lever to its initial position, and a bolt releasing trigger notched at its inner end and pivotally mounted between said arms on said grip, said latch lever being provided with a lug engaging said notch of said trigger whereby the trigger is actuated on the retracting of the latch lever.

4. A door handle comprising in combination a supporting plate, an inwardly projecting bracket on said plate, a chambered pull grip having a longitudinal slot in its inner side, a latch lever pivotally mounted within said grip to be retracted in said slot, a spring acting to bias said latch lever to its initial position, a trigger pivotally mounted on said grip, said latch lever being in direct operative engagement with said trigger whereby the trigger is actuated on the retracting of the latch lever, a bolt lever pivotally mounted on said bracket in coacting relation to said trigger, and a bolt slidably supported on said bracket and pivotally connected to said bolt lever.

5. A door handle comprising in combination a supporting plate, a chambered pull grip having a longitudinal slot in its inner side, a latch lever pivotally mounted within said grip to be retracted in said slot, a spring acting to bias said latch lever to its initial position, a trigger notched at its inner end and pivotally mounted on said grip, said latch lever having a lug in direct operative engagement with the notch in said trigger whereby the trigger is actuated on the retracting of the latch lever, and a bolt lever pivotally mounted in coacting relation to said trigger.

6. In a door handle, the combination of a grip adapted to be mounted on a door to constitute a pull member and having a longitudinal slot in its inner side, a bracket connected to said grip, a latch release lever pivotally mounted on said grip to be retracted into the slot thereof, a spring arranged within said grip to coact with said release lever to return it to its initial position, and a bolt releasing trigger mounted on said bracket and having a notch in the inner end thereof, said release lever being provided with a lug engaging said notch whereby the trigger is actuated upon the actuation of the lever.

7. In a door handle, the combination of a grip adapted to be mounted on a door to constitute a pull member and having a longitudinal slot in its inner side, a bracket connected to said grip, a latch release lever pivotally mounted on said grip to be retracted into the slot thereof, a spring arranged within said grip to coact with said release lever to return it to its initial position, and a bolt releasing trigger mounted on said bracket and having a notch in the inner end thereof, said release lever being provided with a lug engaging

said notch whereby the trigger is actuated upon the actuation of the lever.

8. In a door handle, the combination of a grip adapted to be mounted on a door to constitute a pull member and having a longitudinal slot in its inner side, a latch release lever pivotally mounted on said grip to be retracted into the slot thereof, a spring biasing said release lever to its initial position, a bolt releasing trigger having a notch in the inner end thereof and pivotally mounted on said grip at a point spaced from the pivot of said lever, said release lever engaging said notch whereby the trigger is actuated upon the actuation of the lever, the pivot of said trigger

constituting a stop determining the initial position of said lever.
